UNITED STATES PATENT OFFICE

HARRY E. WHITE, OF CANTON, OHIO, ASSIGNOR TO THE HOOVER COMPANY, OF NORTH CANTON, OHIO, A CORPORATION OF OHIO

SUCTION CLEANER

Application filed September 12, 1930. Serial No. 481,436.

The present invention relates to suction cleaners in general and in particular to improvements in means for controlling the position of the stationary scraping brush in a suction cleaner. More specifically the invention relates to an improved form of stationary-brush-positioning device for a suction cleaner by which the brush is positioned in both working and storage positions by a downwardly directed force.

In an efficient suction cleaner it is desirable to have some form of agitating means to assist the cleaning air which is drawn into the machine at high velocity, in its cleaning function. A common form of agitating means is a stationary brush positioned either in or behind the cleaner nozzle which contacts and brushes the surface covering undergoing cleaning as the machine is moved thereover. Such a brush extends into or below the plane of the lips of the nozzle mouth when in its working position and is preferably provided with position-controlling means by which it can be lifted upwardly from said plane when it is desired that the cleaning shall be entirely performed by air. A common means of positioning the scraping brush is an ordinary lever which is pivoted on the cleaner and which is itself positionable in two positions, namely, an up and a down position. Ordinarily with the lever in the down position the brush would be up or retracted and if it was desired to place the brush in the working position it would be necessary to lift upwardly on the lever. Usually the operator performs this positioning operation with the foot and it has been the teaching of experience that it is objectionable to use the upper surface of the shoe in lifting upwardly on the lever to place the brush in the working position as is required in such a type of positioning mechanism. The use of the upper shoe surface often results in a scratch on the shoe surface and is not as easily accomplished as is the downward push on the positioning lever in which the sole of the shoe is used.

In the brush-positioning mechanism constructed in accordance with the present invention the agitating brush is positioned in both the working and the storage position by

a downward push upon the positioning mechanism by the operator. Such a construction eliminates the aforescribed undesirable upward pull requiring the use of the upper part of the shoe and it has been found to be more positive and satisfactory.

It is an object of the present invention to provide a new and improved form of agitating brush-positioning mechanism for a suction cleaner. It is a further object to provide a new and novel brush-positioning mechanism for suction cleaners in which the agitating brush is positioned in both the working and the storage position by a force which in each case is exerted in the same direction. It is still another object of the present invention to provide a suction-cleaner-stationary-agitating-brush-positioning mechanism in which the brush is positioned in both the working and storage position by means of a downward push which may be applied by the foot of the operator.

Referring now to the drawing, in which a preferred embodiment of the present invention is disclosed:

Fig. 1 discloses a suction cleaner with the present invention embodied therein.

Fig. 2 is a view upon the line 2-2 of Fig. 1.

Fig. 3 is a partial section upon the line 3-3 of Fig. 1.

In the drawing and in Fig. 1 in particular, a suction cleaner of a modern type is disclosed which comprises a main casing 1 which encloses the driving motor for the cleaner and which also forms an exhaust air passage therearound which leads to the exhaust outlet 2 which is provided with suitable means 3 by which a dust bag may be attached. At the forward end of the casing 1 is a unit casting 4 which comprises as in the usual cleaner a suction nozzle 5 and a fan chamber 6 which houses the suction-creating fan which is driven by the motor within the casing 1. The cleaner is movably supported by rear supporting wheels 7, of which only one is shown, and by means of front supporting wheels 8, 8 which are mounted adjustably between the suction nozzle 5 and the fan chamber 6 upon a supporting shaft 9 which is adjustably piv-

oted near its two ends on the downwardly and outwardly extending walls 10, 10 which are positioned at the sides of the casting 4 and formed integrally on the nozzle 5 and 5 the fan chamber 6 for the purpose of improving the appearance of the machine and for the further purpose of providing such supporting means. A pivoted handle 11 is provided which is mounted upon the casing and 10 has its position resiliently maintained by means indicated generally by the reference character 12.

Positioned directly behind the nozzle 5 and adapted to be raised and lowered relative to the plane of the nozzle mouth is the stationary agitating brush 13. Brush 13 is shown in Figure 1 in the raised position being supported with its surface-contacting portion raised from the plane of the nozzle mouth by a carrying member 14 whose forward edge 15 is folded back under and cooperates with suitably downwardly and forwardly projecting lugs 16, 16 etc., to clasp the metallic back 17 of the brush 13. Member 14 is itself supported by rigidly attached arms 18, 18 and together with these members forms a brush-carrying frame which is pivoted by suitable supports 19, 19 within the walls 10, 10. One of the pivotal supports 19 30 is carried directly by a wall 10 while the support 19 for the other arm 18 is carried by a bracket 20 suitably fastened to the adjacent wall 10 as by rivets 21, 21. But supports 19 are positioned sufficiently below the transverse wheel supporting axle 9 to insure absence of interference upon the adjustment of either the brush or the supporting wheels, or both.

Bracket 20 comprises an upper flat surface 22 which contacts the wall 10 and which is provided with an opening 23 in substantial alignment with an opening 24 in that wall. Carried by this upper wall 22 of bracket 20 and extending upwardly thru the opening 24 of the wall 10 is a cylindrical cup member 25 provided at its lower end with a bore of reduced diameter, indicated at 26, which serves to provide an upwardly facing cylindrical shoulder 27 within cup 25. A plunger 28 is slidably positioned within the bore 26 in the cup 25 and is at all times urged upwardly by a coil spring 29 which is positioned between the shoulder 27 in cup 25 and 50 the top of the guide 30, carried by plunger 28 at its upper end, which slidably encloses the outer wall of cup 25. The upward displacement of plunger 28 is limited by means of a pivoted controller member 31 which is 55 carried between the forked lower ends of plunger 28 upon a pin 32 which is itself slidably positioned within a vertical slot 33 in the vertical portion of the bracket 20. The pin 32 performs the useful function of maintaining member 31 in a single plane thru

preventing rotation of the cylindrical plunger 28.

Directly below the plunger 28 and pivoted member 31 is a rotatably mounted member 34 comprising spaced outwardly extending upper arms 35 and 36 which are adapted to be contacted by the lower edge of the pivoted member 31 which is itself formed with inwardly and upwardly directed lower surfaces forming a seat or notch for the purpose of centering either of the arms 35 or 36 with which it makes contact. Circumferentially spaced from the arms 35 and 36 and lower on the rotatable member 34 is still another arm 37 which extends outwardly and which is adapted to contact the extended portion of the adjacent arm 18 of the brush-carrying frame rearwardly of its pivot point 19 where it is provided with a cam surface 38 of such character that with the member 34 rotated so that the arm 37 contacts the cam 38 near its front end the arm 18 is permitted, under the influence of gravity, to be pivoted so that the brush 13 is in the low or working position. With the arm 37 on the rearward part of the cam surface 38 of the arm 18 the extended rearward end of the arm is forced downwardly resulting in the pivoting of the arm, and so the entire brush-carrying frame, about the pivot points 19, 19 and the lifting of the surface-contacting brush upwardly from the covering undergoing cleaning.

In order to prevent unintended variations in the position of the arm-carrying cam-contacting member 34 which, as is seen, controls the position of the cam-carrying arms 18 and so the position of the brush, a friction washer 39 is provided at the support of member 34 which insures that no rotation of that member will occur in the absence of a positive force exerted thereon.

In the operation of the brush-positioning mechanism constructed in accordance with the present invention upon the exertion of a downward force upon the cup or guide 30, and so the plunger 28, the spring 29 is compressed and the plunger 28 advances downwardly. Member 31, being fixed relative to the member 28 in a vertical plane, advances downwardly with it. Rotation of plunger 28 and controller member 31 about a vertical axis is prevented by the pin 32 which slides vertically in the slot 33 thereby insuring the making of contact of controller 31 and arm 35 or 36. Continuing downwardly in advance of plunger 28, member 31 finally contacts one of the two arms 35 and 36 carried by the rotatable member 34, one of said arms being always positioned within the range of the notched under surface or seat of member 31 when it is in the vertical position as it always is upon the beginning of the downward stroke having been so arranged when its upper surface was pulled into contact with the flat undersurface of the cup 25

by the spring 29. Upon contact first being made by the member 31 with an arm 35 or 36 the controller member 31 is pivoted about the pin 32 until the arm 35 or 36 is positioned at the crotch of the notched under side of that member. As member 31 continues downwardly urged by plunger 28 the cam-contacting member 34 is rotated about its axis until those members have reached the bottom of their stroke at which time the removal of the force upon the plunger 28 results in the upward movement thereof under the force exerted by spring 29 and the realinement of the member 31 upon contact with the under-surface of the cup 25. The mechanism is then ready for a repetition of the operation with the difference however, that the other upper arm on the cam-contacting member 34 would be contacted by the controller 31 this time and member 34 would be rotated in the opposite direction with the resultant change of the position of the arm 37 relative to cam 38 and the consequent alteration in the brush position.

As shown in Figure 1 the plunger 28 and controller 31 have just returned to the initial position after having rotated member 34 through contacting and forcing the arm 35 to its furthermost position. Member 31 has just been able to clear the arm 36 of member 34 as it returned to the up position and upon being realined by contact with the underside of cup 25 is so positioned that upon a second downward stroke it will contact, in its notched lower surface, the arm 36 instead of the arm 35 and will cause member 34 to rotate in the opposite direction. As illustrated in Figure 1, with the member 34 positioned as shown, the arm 37 contacts the cam surface 38 of the pivoted arm 18 near its rear end, displacement from either end of said cam surface is prevented by shoulders at the ends thereof, and the brush 13 has been raised from the surface undergoing cleaning. Upon a second push upon the plunger, however, the arm 36 will be rotated clockwise, as viewed in Figure 1, by member 31 and the arm 37 would advance forwardly on the cam surface 38 permitting the arm 18 to pivot in a counterclockwise direction resulting in the lowering of the brush 13 into the plane of the lips of the nozzle 5 and so into contact with the surface covering. It is to be noted that the brush-retaining means provided upon the frame 14 are such that the brush 13 may be removed and replaced by merely sliding lengthwise between the lips 15 and 16, 16 etc.

Having clearly described and illustrated the present invention, I claim:

1. In a suction cleaner a surface-scraping brush and means to position said brush in an operative or an inoperative position comprising a movable member supporting said brush, means to alter the position of said member from any position upon receiving a force in a

single direction, and means to return said positioning means to its initial position independently of said member.

2. In a suction cleaner a surface-scraping brush, means supporting said brush, means for adjusting the position of said supporting means and the brush relative to the cleaner, said means comprising means operable only under a uni-directional force adapted to move said supporting means, and means to retain said supporting means in the position to which it has been moved.

3. In a suction cleaner a surface-scraping brush, a pivoted member supporting said brush, rotatable means carried by said cleaner in operative relation to said pivoted member to adjust angularly said member upon being rotated, and means to rotate said rotatable means, characterized by the fact that said last mentioned means are operable only under a force in a single direction.

4. In a suction cleaner having a suction nozzle, a brush of the stationary scraping type, means movably supporting said brush relative to the plane of the nozzle mouth, manually operable slidable means carried by said cleaner in operative relation with said brush-supporting means for adjusting the position thereof, means to return said manually operable means to initial position and means to retain said supporting means in the position to which it has been adjusted.

5. A stationary brush-positioning mechanism for a suction cleaner comprising a movable brush-supporting frame and means to raise and lower said frame comprising a plunger adapted to receive an actuating force in one direction, means to return automatically the plunger to initial position, and means operatively connecting the plunger to the supporting frame and maintaining said frame stationary upon the return of said plunger to initial position.

6. A tool-positioning mechanism comprising a movable tool-supporting element, an element mounted for linear movement upon the application thereto of a moving force, means resisting any movement of said element and forcing said element to return to initial position upon the withdrawal of the said force, a controller member carried by said movable element, a cam-contacting member in the path of said controller member and mounted for rotation upon being contacted by said controller member, and a cam surface on said tool-supporting element in contact with said cam-contacting member for moving said element upon the rotation of said cam-contacting element.

7. A tool-positioning mechanism comprising a pivoted tool-supporting element, an element mounted for linear movement upon the application thereto of a moving force, means resisting the movement of said element and effecting its return to initial position upon

the withdrawal of the said force, a pivoted controller member having a seat in its lower surface carried by said movable element, a cam-contacting member rotatably mounted 5 in the path of said controller member and provided with a plurality of arms adapted to be singly seated against said controller member for the purpose of rotating said cam-contacting member, and a cam surface formed 10 on said tool-supporting element in contact with said cam-contacting member for pivoting said element upon the rotation of said cam-contacting member.

Signed at North Canton, in the county of 15 Stark and State of Ohio, this 9th day of September, A. D. 1930.
